UNITED STATES PATENT OFFICE

JAMES H. DEVINE, OF CHAMPAIGN, ILLINOIS.

LUNCH BOX

Application filed June 21, 1928. Serial No. 287,105.

This invention relates to food containers, and more particularly to lunch boxes, picnic boxes, and containers of similar nature.

It is known to provide lunch boxes and containers of similar nature having associated therewith either refrigerating or heat radiating means, optionally, for cooling or heating the contents of the box or container as desired. I have found that devices of this character, as commonly constructed, are objectionable in that a very appreciable part of the heating or cooling effect is lost by radiation or conduction, as the case may be. This objection can be avoided by properly disposing the container for the cooling or heat radiating material relative to the food and in such manner that the food itself may be utilized to insulate the tank or container for the refrigerant or the heated substance. By this arrangement, the food is acted upon to the best advantage and the heating or the refrigerant effect produced is materially prolonged and its effectiveness greatly increased. One of the main objects of my invention is to provide a lunch box or kit of neat and attractive appearance which can be readily produced at relatively small cost, and which is highly sanitary and can be readily assembled and disassembled. A further object is to provide a lunch box having a tank or body providing a source of heat or cold, as desired, this body being so supported in a structure associated therewith as to permit the food to be introduced about the body in such manner as to insulate the same and also to be acted upon to best advantage by the heat or the cold, as the case may be, of the body. A further object is to provide a container in which the body is disposed and means associated with the container and a casing therefor whereby the container is effectively insulated from the casing. Further objects and advantages will appear from the detailed description.

In the drawings:

Fig. 1 is a front view of a lunch box constructed in accordance with my invention;

Fig. 2 is a longitudinal vertical sectional view through the box with the cover open;

Fig. 3 is a section taken substantially on line 3—3 of Fig. 2;

Fig. 4 is a side view of the sandwich and tank receiving frame;

Fig. 5 is a section taken substantially on line 5—5 of Fig. 4;

Fig. 6 is a fragmentary sectional view, on an enlarged scale, through the filling neck of the tank and associated parts;

Fig. 7 is a section taken substantially on line 7—7 of Fig. 4, on an enlarged scale;

Fig. 8 is a detail sectional view through one of the top spacing and cushion members of the sandwich and tank receiving frame, on an enlarged scale.

In constructing my lunch box, I provide a suitable casing 1 of rectangular shape in vertical and horizontal section. This casing may be formed of any suitable material, though I preferably use sheet metal, preferably aluminum. The casing may be given a suitable finish to represent wood, in a known manner, or the casing may be covered with leather or other suitable material, so as to present a neat and attractive appearance. A cover 2 is hingedly secured to casing 1 at 3 and may be constructed of the same material as the casing. A suitable handle 4 is suitably secured to the cover, as by being riveted thereto, and the cover is further provided, at its front edge, with a hasp 5 which cooperates with a lock 6 for locking the cover closed. Preferably the cover is also secured by two spring clasps 7 of known type, in a known manner.

A lower container is disposed within the lower portion of casing 1. This container comprises an inner member 8, preferably of glass, which is spaced away from the casing 1 by an outer member 9 formed of cork or other suitable material which is an efficient heat insulator and is also of light weight. I also contemplate insulating the inner member 8 from the casing 1 by a space between this member and the casing; this space being exhausted to provide a vacuum, in a known manner. The inner member or liner 8 of glass is non-corrodible and provides a sanitary container which is not affected by articles of food, thus assuring that the container is maintained in a sanitary condition.

The upper end or top of the lower container is closed by a suitable flanged cover 10 which fits snugly into the upper end of the container so as to form a tight closure therewith. This 5 cover may be constructed of any suitable heat insulating material, such as wood, and is provided with a central depression 11 having a transverse rib 12 which provides a gripping element for removing the cover from the container. The cover 10 is preferably provided with an inner layer 10a of sheet cork or other suitable heat insulating material, or may be formed entirely of such material.

An upper container 13 in the form of a 15 relatively deep tray is mounted in the upper portion of casing 1 and seats upon cover 10. This container 13 is preferably formed of sheet aluminum and is divided by a transverse partition 14 into two compartments, 15 and 16. The compartment 15 is adapted for reception of two one-half pint vacuum bottles or containers though, obviously, this compartment can be used to contain various other articles desired. The compartment 16 is 25 adapted for reception of a supplemental container 17 having a glass liner 18 and insulated from the tray or container 13 by a surrounding layer of cork or other suitable insulating material. This container 17 is also 30 provided with a snugly fitting cover 20 which may be formed of wood, cork, or any other suitable or preferred material, a good insulator of heat being preferably used. The supplemental container 17 is constructed similarly, 35 in all essential respects, to the lower container and, if desired, the insulating layer of cork 19 may be replaced by a space from which the air is exhausted to form a vacuum, in a manner well understood in the art.

40 The lower container receives a frame 21 which is of rectangular shape in plan and in side view, this frame being formed of sheet metal, preferably sheet aluminum. The frame 21 is provided at each end and at its 45 bottom with outwardly projecting spacing members 22 which serve to space the frame from the bottom and end walls of the glass liner 8. Similar spacing members 23 (Fig. 3) are also provided at each end of the frame 50 and project laterally thereof so as to space the frame from the side walls of the liner 8, as illustrated. In this manner, the frame is supported out of contact with the liner and is effectively insulated therefrom, by the spacing 55 elements 22 and 23, which are of relatively small area, so that the flow of heat between the frame and the container by conduction is reduced to a minimum. This is of very material assistance in preventing loss of heat or 60 cold, as the case may be, due to conduction between the frame and the container therefor.

A channel member 24 (Fig. 7), is secured to the inner face of each end wall 26 of frame 65 21. This member is arranged transversely of

end wall 25 and is disposed substantially centrally of such wall. Channel member 24 is closed at one end, at 26, and is provided at its other end with a depending U-shaped flange 27 adapted for reception of the lower portion 70 of a latch plate 28 pivoted at 29 on the upper flange of channel member 24. The channel members receive lugs 30 of elongated rectangular shape which are secured to the ends 75 of a tank 31. This tank is flat and relatively thin, being of rectangular shape transversely and longitudinally.

The tank 31 may be constructed of any suitable material depending largely upon the characteristics of the substance to be placed 80 within the tank. Under ordinary conditions, this tank may be constructed of sheet aluminum. By swinging the latch plate 28 into inoperative position, the tank 31 may be readily slid into or out of the frame 21, the lugs 30 85 travelling in the channel members 24. The tank may be mounted in the frame in any other suitable or preferred manner, though I have found the manner of mounting the tank which I have illustrated and described 90 highly efficient, as permitting ready insertion and removal of the tank.

Tank 31 is provided, in one side wall thereof, with a cylindrical opening 32, in which is disposed a flange neck 33 suitably secured, 95 as by soldering, to the tank wall. This neck is adapted for reception of a suitable closure member, such as a cork stopper 34, and is exteriorly threaded for reception of a suitable cap 35 screwed thereon. Preferably, an expansion spring 36 is confined between the cap 35 and the outer end of stopper 34 and serves to effectively hold the stopper in the neck 33, the stopper and the cap cooperating to prevent leakage of the container through neck 33. Other means than that illustrated may be provided for filling and emptying the tank.

Tank 31 is supported in spaced relation to the top and bottom walls of the frame 21, as illustrated. Suitable trays 37, which may be formed of sheet aluminum, are adapted to fit snugly between the tank and the top and bottom of the frame, these trays and the tank cooperating to close the sides of the frame. The trays 37 are adapted for reception of sandwiches or other articles of food placed therein, as illustrated in Fig. 5.

With the trays inserted into the frame 21, the upper tray rests upon the top wall of the tank, and the lower wall of the tank provides a closure for the top of the lower tray. The sandwiches are thus disposed closely adjacent the tank so as to be readily heated or cooled, thereby, as the case may be, and these sandwiches, in this position, are also utilized to insulate the tank from the frame 21 to a certain extent. If desired, the trays 37 may be omitted and the sandwiches, suitably wrapped in paper, may be inserted between 120 125 130

the tank and the top and the bottom walls of the frame. When disposed in this manner, the sandwiches are very effective in insulating the tank from the frame.

To prevent any vertical looseness or play of the frame 21, I preferably provide suitable cushioning members on the top of the frame. These members are indicated by reference number 38. Each of the members 38 comprises a neck 39 provided at its lower end with a flange 40 which is suitably secured to the top wall of the frame 21, this neck slidably receiving a shank 41 which depends from a button shaped head 42. An expansion coil spring 43 is mounted about member 38 and is confined between head 42 and flange 40. Upward movement of the shank 41 is limited by a pin 44 secured therethrough, this pin passing through slot 45 in neck 39. When cover 10 is depressed into its lowermost or operative position, which occurs when the upper container or tray 13 is in position and the cover 2 is secured closed, the heads 42 of the members 38 are depressed placing springs 43 under compression. These springs serve to effectively hold the frame 21 against any undesirable looseness or play in a vertical direction while also eliminating liability of breakage of the inner glass member or liner 8 of the lower container due to pressure exerted thereon.

In practice, the tank 31 is removed from the frame 21 and is filled with a suitable refrigerant or a suitable heat retaining substance, as desired. If a refrigerant is desired, the tank 31, including the solution therein, may be cooled down by being placed in crushed ice, or a mixture of crushed ice and salt, or in any other suitable manner as by being placed over night in a refrigerator. If it is desired to maintain the sandwiches or other articles of food hot, the tank may be filled with boiling water or with a suitable solution which has been heated. A solution of an organic substance, such as glycerine, is preferably used. Obviously, after having once been filled, instead of heating water or a solution and pouring it into the tank, the tank and the contents thereof may be heated as a unit in any suitable manner. The tank is then replaced in frame 21 and the sandwiches or other articles of food, either with or without the trays 37, are inserted into the frame between the top and bottom walls hereof and the tank. The frame, together with the tank and the sandwiches, as well as the trays 37, if used, is then replaced in the lower container as a unit, after which the upper container 13 is replaced and the box is closed.

The container 17 is intended for reception of fruit, preserves, and other articles of food. The glass lining 18 of this supplemental compartment assures that it will be maintained in a neat and sanitary condition, since the fruit juices will not attack the glass lining.

While I have illustrated and described my invention as applied to a lunch box, it is well adapted for other purposes as by making it in larger sizes, it is capable of containing relatively large quantities of food stuffs for 70 picnics and other purposes.

Since the frame 21 is effectually insulated from the lower container, and the tank 31 is, in great part, insulated from frame 21, loss of heat or cold from the tank 31 due to conduction between the outer casing 1 and the tank and associated parts is reduced to a minimum. 75

As a result, the articles of food which are disposed closely adjacent the tank will be kept in the desired condition for a relatively long period of time. This produces a device of high efficiency but simple and inexpensive construction which may be readily assembled and disassembled for storing the food and giving access thereto. 80

The inner surface of case 1 is preferably highly polished to reflect heat. This is of advantage as decreasing the loss of heat by radiation, and contributes to the efficiency of the box when used for heating articles of food. 85

As will be understood by those skilled in the art, and as above indicated, changes in construction and arrangement of parts of the invention may be resorted to without departing from the field and scope of the same, and I intend to include all such variations, as fall within the scope of the appended claims, in this application, in which the preferred form only of my invention is disclosed. 90

What I claim is:

1. In a lunch kit, a casing, a container within the casing and thermally insulated therefrom, a frame removably mounted in the container and open at one side, channel members secured to the inner face of each end wall of the frame and extending transversely thereof, and a tank having end lugs fitting into the channel members and cooperating therewith to support the tank substantially centrally of the frame. 105

2. In a lunch kit, a casing, a container within the casing and thermally insulated therefrom, a frame removably mounted in the container and open at one side, open ended channel members secured to the end walls of the frame and disposed transversely thereof, a tank having end supporting lugs slidable into and out of said members, and removable means for closing the ends of the channel members against withdrawal therefrom of said lugs. 115

3. In a lunch kit, a casing, a container within the casing and thermally insulated therefrom, a frame removably mounted in the container, and open at one side, and a tank insertible into and removable from the frame, said tank and the frame having cooperating channel elements and projections for supporting and guiding the tank, and means co- 120

operating with said projections for releasably securing the tank in the frame.

4. In a lunch kit, a casing, a container within the casing and thermally insulated therefrom, a frame removably mounted in the container and open at one side, a tank insertible into and removable from the frame, means for guiding and supporting the tank, and means for releasably securing said tank in the frame.

In witness whereof, I hereunto subscribe my name this 16 day of June, 1928.

JAMES H. DEVINE.
